ALBEN E. LUNDELL, OF NEW YORK, N. Y., ASSIGNEE TO WESTERN ELECTRIC COMPANY,
INCORPORATED, OF NEW YORK, N. Y., A CORPORATION OF NEW YORK.

TELEPHONE-EXCHANGE SYSTEM.

1,234,187.

Specification of Letters Patent. Patented July 24, 1917.

Application filed May 25, 1916. Serial No. 99,750.

To all whom it may concern:

Be it known that I, ALBEN E. LUNDELL, a citizen of the United States, residing at New York, in the county of Bronx and 5 State of New York, have invented certain new and useful Improvements in Telephone-Exchange Systems, of which the following is a full, clear, concise, and exact description.

This invention relates to telephone exchange systems employing machine switching, and particularly to the type of system shown in U. S. Patent No. 1,168,319, to A. E. Lundell, issued January 18, 1916, and is an improvement upon such system.

15 The invention has to do with a selector circuit such as shown in said patent, and its object is to reduce the time interval between the termination of the directive movement of said selector, under control of the 20 sender, and the seizure of an idle trunk leading to the next selector.

The invention will be best understood when described with reference to the accompanying drawing, which shows only so 25 much of the telephone exchange system of said patent as is necessary for a comprehension of this invention.

The selector switch is shown diagrammatically at T, and, as shown and described 30 in detail in said patent, comprises a brush carrier 49 having a number of sets of brushes b fixed thereto, one for each section or division of trunk terminals t. These 35 brushes are normally held latched out of operative relation to the sections they serve, and any set may be tripped, as described in said patent, by the corresponding finger on a trip rod 64, which rod is rotated by a trip magnet 228. The set tripped depends on 40 the distance the carrier 49 is elevated by shaft 50 before the trip magnet is operated; and, in turn, the distance the carrier is elevated before the trip magnet is operated depends on the number of segments of the A 45 commutator wiped over by brush 55 before the sender S is satisfied, all as shown and described in said patent. Each division of the panel, served by a set of brushes b, will be subdivided into groups of trunk terminals, the number of which and the number 50 of terminals in a group being optional.

After the trip magnet 228 is operated, the carrier is again elevated, first to pick out the desired group under the control of 55 the sender S, and then to hunt therein for

an idle trunk, independently of the sender. S indicates the sender. 17, 23, 39 indicate springs of the sequence switch associated with the first selector. 15, 25, 26 indicate the brushes and 14, 27, 37 the terminals of 60 such first selector, which, it will be assumed, has already been set under control of the sender S. The sequence switch springs to the right of the dotted line belong to the second selector sequence switch 40, which is 65 normally in position 1.

The operation of the system will now be described in detail, as by following the operations, it is thought the invention will be most readily understood. After the first 70 selector has been set on the trunk terminals 14, 27, 37, the following circuit is closed to initiate the brush selecting operation at the second selector: free pole of battery, relay 212, second selector sequence switch contact 75 11, conductors 12 and 13, terminal 14, first selector brush 15, conductor 16, sequence switch spring 17 of the sequence switch associated with the first selector and its lower contact, conductor 18, relay 19, armature 80 and back contact of relay 20, sequence switch spring 21 of the sequence switch controlling the sender, conductor 22, first selector sequence switch spring 23 and its top contact, conductor 38, first selector brush 25, terminal 27, conductor 28, second selector sequence switch contact 29 and its lower contact, to ground. Relay 212, in attracting its right armature, locks itself over conductor 30 and second selector sequence switch contact 31 90 to conductor 13, independently of contact 11. In attracting its left armature, it closes the following circuit for relay 32: free pole of battery, relay 32, conductor 33, second selector sequence switch contact 34, conductor 35, left armature and front contact of relay 212 to ground. Relay 32, in attracting its left armature, locks itself over conductor 36, terminal 37 and first selector test brush 26 and sequence switch spring 39, 100 to ground at the first selector. In attracting its right armature, it closes the following circuit to move the second selector sequence switch 40 from position 1 to position 2: free pole of battery, sequence switch motor magnet 41, conductors 42, 43, second selector sequence switch spring 44, armature and front contact of relay 32 to ground.

In position 2, the following circuit is closed for the magnet 220 to elevate the 110

brush carrier 49: free pole of battery, magnet 220, conductor 46, second selector sequence switch contact 47, conductor 35, left armature and front contact of relay 212 to ground. Magnet 220, in attracting its armature 48, forces brush carrier 49 against a constantly rotating shaft 50 to elevate the brush carrier 49. Fixed to the upper end of carrier 49 is an arm 53, carrying three brushes 54, 55, 56, adapted to wipe over commutator plates B, A, C, respectively, as shown in detail in the patent heretofore mentioned. For each metallic segment of the commutator A passed over by the brush 55 as the carrier 49 is elevated, a shunt circuit is closed about the stepping relay 19 at the sender. This shunt circuit may be traced as follows: free pole of battery, relay 212, conductor 30 and second selector sequence switch contact 31, conductor 12, conductor 13, second selector sequence contact 61, conductor 62, segment of commutator A, brush 55 to ground. Each time this shunt circuit is closed, the relay 19 at the sender is deenergized, and when such sender is satisfied, the cut-off relay 20 thereat operates, as shown in detail in the patent referred to. Relay 20, in attracting its armature, opens the circuit of relay 212. Relay 212, in retracting its left armature, opens the circuit of elevating magnet 220, whereupon the carrier 49 comes to rest with a predetermined set of brushes b, in operative relation to the corresponding tripping finger on the trip rod 64, as shown in the patent referred to. The carrier 49 is held elevated by retaining pawl 65. The retraction of the left armature of relay 212 closes the following circuit to move the second selector sequence switch from position 2 to position 3: ground, left armature and back contact of relay 212, second selector sequence switch contact 66, conductors 43, 42, second selector sequence switch motor magnet 41, free pole of battery. The second selector sequence switch thus moves from position 2 to position 3.

In position 3, trip magnet 228 is energized, which, in attracting its armature, 50 twists the trip rod 64 to interlock a finger on the said rod and a lever on the holder of the predetermined brush set b, the remaining trip fingers passing through the line of travel of their respective trip levers 55 to the other side thereof, as shown in the patent referred to. In position 3, the following circuit is closed to again energize relay 212: free pole of battery, relay 212, conductor 63, second selector sequence switch contact 11, conductors 12 and 13, terminal 14, brush 15, conductor 16, first selector sequence switch spring 17 and its bottom contact, relay 19, armature and back contact of relay 20, now again closed, sender sequence switch spring 21, conductor 22, first selector

sequence switch spring 23 and its upper contact, brush 25, terminal 27, conductor 28, second selector sequence switch spring 29 to ground. Relay 212, as before, locks itself to conductor 13. Relay 212, in attracting 70 its left armature, closes the following circuit to energize the relay 67: free pole of battery, left winding of relay 67, conductors 68, 69, second selector sequence switch spring 70, conductor 35, left armature and 75 front contact of relay 212 to ground. Relay 67, in attracting its left armature, closes the following circuit to move the sequence switch 40 to position 4: free pole of battery, magnet 41, conductor 42, contact 170, conductor 74, left armature and front contact 80 of relay 67 to ground.

In position 4, the following circuit is closed for the elevating magnet 220: free pole of battery, magnet 220, conductors 46 85 and 72, second selector sequence switch contact 73, conductor 74, left armature and front contact of relay 67 to ground. The magnet 220, in attracting its armature 48, again forces the brush carrier 49 against the 90 constantly rotating shaft 50, to elevate the carrier under control of the sender, to the beginning of the group in which hunting is to take place. At the beginning of the upward movement, the selected set of brushes 95 is tripped so as to be in position to wipe over the terminals of its group. During this elevating movement, the brush 54 wipes over segments of the commutator B. Each time the brush 54 engages one of the segments of 100 commutator B, the following shunt circuit is closed about the relay 19 at the sender: free pole of battery, relay 212, its armature and front contact, conductor 30, second selector sequence switch contact 31, conductors 105 12 and 13, second selector sequence switch spring 76, conductor 77, segments of commutator B, brush 54 to ground. The stepping relay 19 is deenergized once for each segment passed over by the brush 54, and 110 when the required number of operations of this relay have ensued to satisfy the sender, the relay 20 thereof is energized to open the circuit of relay 212 to deenergize the elevating magnet 220, all as shown in the patent 115 referred to. The arrangement is such that, at this instant, the test brush b' of the released set of brushes is in contact with the test terminal t' of the first trunk, and relay 212, in retracting its left armature, will, if such 120 trunk is idle, result in the deenergization of relay 67, which, in retracting its left armature, will open the circuit of the elevating magnet 220 and stop the brush carrier 125 with the brushes b on the first set of terminals t of the selected group of trunks. Busy trunks are those whose test terminals t' are grounded, as will be hereinafter described. Consequently, when the relay 20 at the 130 sender opens the circuit of relay 212 at the

end of group selection, relay 67 will remain energized over a circuit including its right winding, its armature and front contact, sequence switch contact 78, conductor 79, test brush b' , grounded test terminals t' of busy trunks. While the test brush b' is passing between terminals, relay 67 is maintained energized over the following circuit: free pole of battery, left winding of relay 67, 10 conductors 68, 96, sequence switch contact 97, conductor 98, segments of commutator C, brush 56, conductors 99, 100, sequence switch contact 101, conductor 74, left armature and front contact of relay 67 to ground. Relay 15 67, in remaining energized, maintains closed the circuit of the elevating magnet 220, which continues the movement of the brush carrier 49, in search of an idle trunk. When a trunk is reached whose test terminal t' is 20 not grounded, relay 67 will become deenergized, and in retracting its left armature, will open the circuit of elevating magnet 220, thus stopping the brush carrier 49 with the brushes b' , b^2 , b^3 in engagement with the terminals t' , t^2 , t^3 respectively, of such idle 25 trunk. The carrier 49 is held elevated by retaining pawl 65. Relay 67, in deenergizing, closes the following circuit to move the second selector sequence switch 40 out of 30 position 4: free pole of battery, second selector sequence switch motor magnet 41, conductors 42, 43, second selector sequence switch contact 80, conductor 81, left armature and back contact of relay 67 to ground. 35 The sequence switch moves, under control of its contact a , to position 6, where it comes to rest.

In position 6, the closure of second selector sequence switch springs 82, 83 extends 40 the conductors 13, 28 leading from the sender to the brushes b^2 , b^3 , now in engagement with terminals t^2 , t^3 , from which conductors 84, 85 lead to the next selector to be set.

45 When all the switches to the connection have been set, under control of the sender S, the first selector sequence switch is moved out of position 11 and into position 12, in which the calling line E is extended through 50 to the called line, and the sender is cut off from the talking leads 16, 38.

Upon the termination of the conversation, the circuit of relay 32 is opened at a preceding switch by the opening of a contact 39 thereat, as shown in the patent mentioned. This relay, in retracting its right armature, closes the following circuit for the second selector sequence switch motor magnet 41: free pole of battery, magnet 41, 55 conductors 42, 43, second selector sequence switch contact 87, right armature and back contact of relay 32 to ground. The closure of this circuit moves the second selector sequence switch out of position 6, whereupon a circuit is closed through the contact

60 a of the sequence switch, which is closed continuously from 6 to 18, in which position the sequence switch comes to rest. In position 18, the following circuit is closed for a restoring magnet 264: free pole of battery, magnet 264, conductor 89, second selector sequence switch spring 90 and its bottom contact, to ground. This magnet, in attracting its armature 91, withdraws the retaining pawl from the brush carrier 49, 65 and forces the carrier into engagement with a constantly rotating shaft 92, adapted to lower the carrier. When the carrier reaches its normal position and brush 54 engages commutator segment D, the following circuit is closed to drive the sequence switch from position 18 to normal: free pole of battery, magnet 41, conductor 42, sequence switch contact 150, commutator segment D, brush 54 to ground. 70

75 The apparatus is now restored and may be used in establishing another connection.

What is claimed is:

1. In a telephone exchange system wherein an automatic switch is power-driven under control of a sender, the combination with the switch and sender, a continuously operating driving mechanism, trunks terminating in said switch in groups, test terminals therefor, a magnet for operatively connecting said switch to said mechanism to drive the switch, a power control relay adapted when operated to energize said magnet, a line relay at said switch in circuit with said sender and energized only while said sender is operating, a circuit for said power control relay closed at a front contact of said line relay, and a substitute circuit for said control relay including test terminals of busy trunks. 90

95 100 105

2. In a telephone exchange system wherein an automatic switch is power-driven under control of a sender, the combination with the switch and sender, trunks terminating in said switch in groups, test terminals therefor, a power shaft, a magnet for coupling said switch to said shaft, a power control relay adapted when operated to energize said magnet and having two windings, a line relay at said switch in circuit with said center and energized only while said sender is operating, a circuit including a winding of said power control relay closed at a front contact of said line relay, and a substitute circuit including the other winding of said control relay and test terminals of busy trunks. 110

115 120

3. In a telephone exchange system wherein an automatic switch is power-driven under the control of a sender, the combination with the switch and sender, a continuously moving shaft, trunks terminating in said switch in groups, test terminals therefor, a magnet for coupling said switch to said shaft, a power control relay for said mag- 125

130

net, a line relay at said switch in circuit with said sender and energized only when said sender is operating, a circuit for said power control relay including a contact of 5 said line relay, and means including said power-control relay and circuits including said test terminals for maintaining said

magnet energized after the deenergization of said line relay if the switch encounters busy trunks.

10

In witness whereof, I hereunto subscribe my name this 24th day of May, A. D., 1916.

ALBEN E. LUNDELL.
